K. ZACK

SAFETY CATCH FOR BROOCHES AND THE LIKE

Filed May 1, 1923

Karl Zack.
INVENTOR.

BY

Mason Fenwick Lawrence. ATTORNEYS.

UNITED STATES PATENT OFFICE.

KARL ZACK, OF DENVER, COLORADO.

SAFETY CATCH FOR BROOCHES AND THE LIKE.

Application filed May 1, 1923. Serial No. 635,988.

To all whom it may concern:

Be it known that KARL ZACK, a citizen of the United States, residing at Denver, in the county of Denver and State of Colorado, has invented certain new and useful Improvements in Safety Catches for Brooches and the like; and he does hereby declare the following to be a full, clear, and exact description of the invention, such as will 10 enable others skilled in the art to which it appertains to make and use the same.

This invention relates to improvements in safety catches for brooches, bar-pins and the like, and has for its object to provide a catch which will not become accidentally opened. Briefly stated the invention consists in the provision of a slidably and pivotally mounted latch in connection with its keeper, means being provided to hold the 20 latch against sliding movement after the same has been closed.

The various novel features of the invention will appear from the detailed description taken in connection with the accompanying drawing forming part of this specification.

In the drawings, Fig. 1 is an end elevation of the improved safety catch showing the same in locked position.

30 Fig. 2 is a side elevation of the same.

Fig. 3 is an end elevation showing the same in opened position.

Fig. 4 is a side elevation looking at the back of the keeper, the lock being open.

35 Fig. 5 is a plan of Fig. 4.

Fig. 6 is a vertical section on line 6-6 of Fig. 3.

Fig. 7 is an end elevation of the keeper and Fig. 8 is a view showing the application of the invention to a brooch or bar.

In the drawings numeral 1 indicates the body of the brooch or bar, with which the improved catch may be employed, and numeral 2 designates the pin proper which is pivoted at one end to the body 1 and at its other end is adapted to be received within the lock. The keeper is indicated at 3 and is provided with a hook shaped end having a notch 4 in the top thereof which 45 is adapted to form a seat for a projection 5 at the free end of the latch 6, which is pivoted on a pin 7 mounted in the keeper. The keeper is provided with a cut-out as indicated at 8 and is of sufficient length 50 to allow the latch to be shifted along the

pin for a short distance. This distance is determined by the width of a lateral shoulder 9 on the latch 6 adjacent the bearing opening in the latch.

This shoulder is adapted to be disposed in front of a shoulder 10 on the keeper 3, said shoulders when in abutting relation serve to prevent relative turning movement between the keeper and the latch. When the latch is slid or moved on the pin 7 away 60 from the shoulder 10 it may be turned upon its pivot 7 and swung open as shown in Fig. 3.

The opening 8 extends through the keeper 3 from one side to the other and mounted near the base of the keeper is a finger 11 which is adapted to be swung toward the pin 7 in the path of slidable movement of the latch 6, when the latch is in closed position as in Fig. 1. When the finger is disposed in the position stated the latch 6 may 70 not be slid along the pin 7. The finger 11 is mounted in any suitable manner as on a pin 12, and when in closed position will lie flush with the back of the keeper. 75

The latch 6 is provided with an extension 13 which when the latch is in locked position as shown in Fig. 1, will extend beneath a shoulder 14 constituted by the cut-out in the keeper. The shoulder 14 and the extension 13 also serve in connection with the shoulders 9 and 10 to hold the latch against turning movement. When the latch is in closed position the rounded heel of the extension or projection 13 will be disposed 80 quite close to the pin 12 on which the finger 11 is mounted and consequently, when the finger is swung into functioning position it will be disposed along the side of the heel of the projection 13 as is clearly illustrated 85 in Fig. 1.

The finger 11 is cut away on its inside and terminates in a point-like member so that the finger can be readily gotten ahold of by the fingers of the hand when it is desired to 90 unlock the improved catch. The latch 6 is provided with a rib 15 which will serve as a finger hold or abutment for the fingers of the hand when it is desired to shift the latch on its pin 7. 95

The operation will be readily understood. When it is desired to insert the pin 2 into the catch the latch is opened as in Fig. 3. After the pin has been disposed beneath the hooked part of the 100 105 110

keeper the latch is swung on its pivot and the knob or projection 5 thereof sprung over the end of the latch until the knob is seated in the recess or pocket 4 in the top 5 of the keeper. The latch is then shifted along the pin 7 to the limit of its movement in which position the shoulders 9 and 10 would be in abutting relation as shown in Fig. 1 and the extension 13 of the latch 10 will underlie the shoulder 14 of the keeper. Thereupon the finger 11 is swung into closed position with the result that the same forms a stop which will prevent shifting of the latch 6 on the pin 7.

15 What is claimed is:

1. The combination with a keeper, of a latch pivotally and slidably mounted thereon the latch being locked against turning when at one end of its slidable limit and 20 freely turnable when displaced from said limit, and releasable stop member cooperating with the latch to hold the same against sliding movement.

2. The combination with a keeper, of a latch pivotally and slidably mounted thereon, cooperating means on the keeper and latch adapted to interlock when the latch is at one limit of its sliding movement and a swingable stop adapted to be disposed 30 across the path in which the latch is slidable when the latter is interlocked with the keeper.

3. The combination with a keeper, of a latch pivotally and slidably mounted thereon, cooperating means on the keeper and latch adapted to interlock when the latch is at one limit of its sliding movement, a finger pivoted to the keeper at a recess there-

in and adapted to be disposed across the path in which the latch is slidable. 40

4. In combination, a keeper having an opening extending therethrough, a pin bridging the opening, a latch pivotally and slidably mounted on the pin, co-mating means between the latch and keeper for holding the latch against turning movement when at one end of its slidable limit on the pin, an extension on the latch extending beyond the said pin, and a finger pivoted on the keeper and adapted to be disposed adjacent said extension when the latch is held in non-turning position. 50

5. In combination, a keeper having a reentrant portion, a latch pivoted to the keeper and disposable in front of the said portion, 55 a pin on which the latch is slidable and on which it pivots, a lateral shoulder on the latch, an abutment on the keeper, said shoulder and abutment adapted to prevent turning of the latch when the latch is at one end of its slidable limit, and a finger pivoted on the keeper and adapted to be disposed across the slidable path of the latch.

6. In combination, a keeper, a latch pivoted intermediate its ends to the keeper said keeper having a cut-out portion within which one end of the latch may swing, and a finger disposable adjacent that end of the latch within the cut-out said cut-out being of a length to allow sliding movement of the 70 latch on its pivot, and interengaging means between the latch and keeper for holding the latch against turning movement when the latch is at one limit of its slidable limit.

In testimony whereof I affix my signature.

KARL ZACK.
